TELLTALE DEVICE

David C. Rockola, Chicago, Ill.

Application August 28, 1935, Serial No. 38,163

5 Claims. (Cl. 116—114)

This invention relates to a tell-tale device.

It is an object of this invention to provide an improved game apparatus which is relatively simple and inexpensive in construction and 5 efficient in use.

Another object of the present invention is to provide an improved tell-tale device for indicating when a machine, device or apparatus, in which the same is mounted, has been tilted from 10 its play or operating positions, as in an attempt to operate the same fraudulently without payment of a proper coin.

A further object of the present invention is to provide a novel and improved tell-tale device 15 especially adapted for use in conjunction with amusement game apparatus and adapted to indicate when the apparatus has been tilted or tipped from its proper operating position for any reason, as by the player attempting to operate 20 the same fraudulently without payment of a proper coin.

Other objects will appear hereinafter.

The invention consists in the novel combination and arrangement of parts to be hereinafter 25 described and claimed.

The invention will best be understood by reference to the accompanying drawings, showing the preferred form of construction and in which:

Fig. 1 is a fragmentary perspective view of a 30 game apparatus embodying a preferred form of the new tell-tale device;

Fig. 2 is an enlarged sectional view on line 2—2 in Fig. 1;

Fig. 3 is an enlarged sectional view on line 3—3 35 in Fig. 2;

Fig. 4 is a sectional view on line 4—4 in Fig. 3; and

Fig. 5 is a fragmentary bottom perspective 40 view of the parts shown in Fig. 3.

A game apparatus embodying a preferred form 45 of the new tell-tale device is shown in the drawings, is therein generally indicated at 10, and comprises a cabinet 11 which includes a substantially horizontal wall or member 12, the member 12 being arranged adjacent the playing member 13.

The new tell-tale device is generally indicated 50 at 14, in the drawings, and comprises a substantially cylindrical tell-tale member 15, this tell-tale member 15 having a frusto-conical base 16 which is adapted to rest in a corresponding seat or opening 17 which is formed in the member 12 so as to hold the tell-tale member 15 in upright or vertical position, as in full lines, Fig. 2.

Attached to the tell-tale member 15 at the lower

end of the latter is a flexible element or chain 18. Having one end attached to the chain 18 at the lower end of the latter is a coil spring 19, the other end of the spring 19 being attached to an arm 20 of a resetting member which is generally indicated at 21. This resetting member 21 is pivotally mounted between its ends, as at 22, upon a supporting bracket 23 which depends from the wall 12 of the cabinet 10.

Slidably mounted on a wall 24 of the cabinet 11 is a coin slide or carriage, which is generally indicated at 25, and this carriage has a handle portion 26 which projects exteriorly of the cabinet 11 through a slot 27 formed in the wall 24 of the cabinet 11 (Fig. 1). Slide 25 also has a serrated edge 62 engageable by a full-stroke locking pawl 64, which prevents return of the slide 25 from any but its full-stroke position.

Formed in the wall 24 of the cabinet 11, adjacent the slot 27, is a coin receiving aperture or slot 28 (Figs. 1 and 3) and mounted in the cabinet 11, on the inner side of the wall 24, is a trackway 29 which consists of two spaced horizontal rails 30; the carriage 25 includes a portion 31 which projects laterally across the rails 30 of the trackway 29 above the latter (Fig. 2).

The pivoted member 21 includes an arm 32 and this arm 32 is adapted to be projected into, and to work in a space or slot 33 which is provided between the portion 31 of the carriage 25 and the body 34 of the same (Fig. 2).

Having one end attached to the arm 20 of the pivoted member 21, as at 36, is a resetting spring 35, the outer end of which is fixed in the cabinet 11, as at 37, and the spring 35 normally urges the 35 pivotal member 21 in a clockwise direction (Figs. 3 and 5).

Pivotedly mounted between its ends in the cabinet 11, as at 38, is a latch member 39. This latch member 39 has an arm 40 which projects 40 into the path of the lateral extension 48 of the slide carriage 25. The latch member 39 also includes an arm 42 which is latchingly engageable with an arm 43 of the pivoted member 21. The end of the arm 42 of the latch member 39 45 is provided with a notched portion 44 which engages with a lateral extension or arm 45 which is formed on the arm 43 of the pivotal member 21.

The flexible element or chain 18 works around a 50 guide 46.

Normally urging the slide carriage or coin slide 25 (right to left, Figs. 3 and 4) into its initial position, is a spring 47.

Formed in the arm 32 of the member 20 is a 55

notched portion 49 and adjacent the notch 49 is a coin engaging or bearing edge 41.

Only so much of the coin and resetting mechanism is recited as is believed necessary to an understanding of the operation of my tell-tale device, the resetting mechanism being subject matter disclosed and described in my co-pending application Serial Number 18,175, for Game apparatus, filed April 25, 1935.

10

Operation

If the cabinet 11, for any reason, is tilted from its normal or proper operating position, such as for the purpose of fraudulently operating the game apparatus, the tell-tale member 15 falls from its upright or vertical position in which it stands otherwise undisturbed by, and independent of the game element of the apparatus, into a substantially horizontal position, wherein it rests upon its supporting base 12, as shown in dotted lines (Fig. 2), and when in this position the tell-tale member 15 indicates that the cabinet 11 has been moved from its proper operating position, the tell-tale being clearly visible in all indicating positions at all times to the operator or proprietor of the device through the glass walls of the usual cabinet in which the game apparatus is housed, as shown in the illustrations of the drawings.

When a coin "A" is inserted into the coin slot 28 it falls by gravity upon the rails 30 of the trackway or guideway 29, into position shown in Figs. 2 and 4, and in this position the coin projects into the notched portion 49 which is formed in the arm 32 of the member 20. The operator then grasps the handle 26 of the coin slide or carriage 25 and moves the same (right to left, Fig. 1, left to right, Fig. 3), whereupon the coin engages the member 21 and the portion 31-32 and pivots the same (counterclockwise, from full to dotted line position, Fig. 3). During this movement of the coin slide 25 (left to right, Figs. 3 and 4) the arm 20 of the member 21-32 acts upon the flexible element or chain 18 to pull the latter around the guide 46, thereby raising the tell-tale member 15 into upright position, as in full lines, Fig. 2.

As the coin slide 25 reaches the end of its operative or full stroke, (to the right, Figs. 3 and 4) and the member 20 reaches dotted line position, Fig. 3, the angled end portion 45 provided on the arm 43 of the member 20 engages in the notched position 44 of the latch member 39, and this latching engagement between the notched portion 44 of the latch member 39 and the angled arm 45 of the member 20 is maintained by a spring 52 (Fig. 3) which acts upon the latch member 39 to pivot the same (counterclockwise, as seen in Fig. 3).

However, the coin disposed on the trackway 29-30 is eventually moved to the right hand end of the latter (Fig. 3), or left end of Fig. 5 by means 60 to be hereinafter explained and falls off the trackway 29-30, into a suitable receptacle, which may be provided therefor in the cabinet 11, subsequent to the time when the slide 25 reaches full stroke position, wherein it is stopped by engagement of the handle 26 with a stop 50 which is provided on the end wall 24 of the cabinet 11.

When the player releases the coin slide 25 and its handle 26, the resetting spring 47 of the coin slide 25 returns the latter to its initial position 70 (right to left, Figs. 3 and 4) and this movement of the coin slide 25 (from right to left, Figs. 3 and 4) releases the coin from its wedged position between the bearing edge 41 of the pivoted member 21, which will remain in dotted line position (Fig. 3) because of its latching engagement with

the latch arm 39 at 45-44, and the angled end portion 45 of the cam slide 25 thus allowing the coin to drop by gravity into a suitable receptacle which may be provided therefor in the cabinet 11.

As the coin slide 25 approaches its initial or coin-receiving position, the extension 48 of the coin slide 25 engages the end portion 51 of the latch member 39, and thereby pivots the latter (clockwise, Fig. 3). This movement of the latch member 39 releases the notched portion 44 thereof from latching engagement with the angled end portion 45 of the arm 43 of the member 21, whereupon the tensioned resetting spring 35 acts upon the member 21, to pivot the latter (clockwise, from dotted to full line position) into its initial position, as in full lines, Fig. 3, thereby registering the notched portion 49 and the edge 41 of the member 21 with the coin slot 28, so that the foregoing cycle of operations may be repeated.

The coin slide mechanism includes an elongated 20 bar member 66 having a cammed edge (Figs. 3, 4, 5) and secured to the wall 24 co-extensively with rails 30 and at a higher level therefrom. It will be observed from Fig. 4 that the coin "A" carried on rails 30 (left to right) by arm 31 will encounter the cammed edge of bar 66, and as the coin approaches the right end of rails 30, it will be urged off the rails by member 66.

It is understood that the coin slide mechanism, including the pivoted bifurcated arm members 32-43 are adapted to reset an associated game apparatus, as by the shaft 22 (Figs. 3 and 5) which may be keyed to the arms 32-43 and be operatively associated with any game mechanism below base or wall 12.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a game device of the character described the combination of; a support having a recess formed therein; a tell-tale member movably mounted upon said support and having its lower end portion normally disposed in said recess so as to hold said tell-tale member in an upright or substantially vertical position when the said support is disposed in its normal or proper operating position, but said tell-tale member being normally undisturbed by proper operation of the game and being movable by gravity into a substantially horizontal position if and when the said support is moved from its normal and proper operating position as by fraudulent means; and means for moving said tell-tale member into its normal or upright position after operation thereof.

2. In a game device of the character described the combination of a support; a tell-tale member movably mounted upon said support for operation independent of the normal or authorized operation of the game, and normally disposed in upright or vertical position thereon when the said support is in its normal or proper operating position but said tell-tale member being adapted to move by gravity into a position at an angle to the vertical if and when the said support is moved from its normal or proper operating position as by fraudulent attempt to operate said game; and

means for resetting the said tell-tale member into its normal or upright position after operation thereof.

3. In a game device of the character described, 5 the combination of; a support; a tell-tale member movably mounted upon said support for operation independent of the normal game operation per se and normally disposed in an upright or vertical position thereon when the said support is in its normal or proper operating position but said tell-tale member being adapted to move by gravity into a position at an angle to the vertical if and when the said support is caused to move from its normal or proper operating position 15 by fraudulent or like tilting of the game device; and means for resetting the said tell-tale member into its normal or upright position after operation thereof; said resetting means including a member slidably mounted in said cabinet or 20 casing and having a handle disposed exteriorly thereof.

4. In a game device of the character described, the combination of; a support; a tell-tale member movably mounted upon said support and normally disposed in an upright or vertical position but said tell-tale member being adapted to move independently of the normal or proper operation 25 of the game into a position at an angle to the

vertical if and when the said support is moved from its normal or proper operating position as by fraudulent disturbance of said game device; and means for resetting the said tell-tale member into its normal or upright position after 5 operation thereof; said resetting means including a member movably mounted in said cabinet or casing and having a handle disposed exteriorly thereof.

5. In game devices or the like, a tell-tale mechanism comprising a support adapted for operative association with said game device, a member movably mounted in said support to stand in an upright or vertical position therein, such position corresponding to the normal operating position 15 of a said game device, the said tell-tale member being adapted to move by gravity into a position away from the vertical independently of the normal or authorized operation or playing of a game, and responsive to unauthorized or fraudulent 20 movement of said game device, together with resetting means for said tell-tale member, the said means including a flexible connection between the lower or support end of said tell-tale member and a game operating member whereby the said 25 tell-tale member may be moved into vertical position in said support.

DAVID C. ROCKOLA.
